COMBINED ACCESS DOOR AND FRAME
THEREFORJohn C. Kurz, Philadelphia, Pa., assignor to Advanced
Air, Inc., Philadelphia, Pa.

Filed Dec. 8, 1971, Ser. No. 206,230

Term of patent 14 years

Int. Cl. D23—04

U.S. CL. D23—163

FIG. 1

FIG. 8

FIG. 2

FIG. 5

FIG. 3

FIG. 6

FIG. 4

FIG. 7

FIG. 1 is an exploded view of a combined access door and frame therefor showing my new design, the air duct being shown in broken lines for illustrative purposes only.

FIG. 2 is an enlarged bottom plan view thereof.

FIGS. 3 and 4 are respectively enlarged end and side elevational views thereof.

FIG. 5 is an enlarged top plan view of the door, the frame being omitted for purposes of illustration.

FIGS. 6 and 7 are respectively enlarged end and side elevational view of the door, the frame being omitted for purposes of illustration.

FIG. 8 is a bottom perspective view of the combined access door and frame therefor.

I claim:

The ornamental design for a combined access door and frame therefor, as shown and described.
